SCRAPER FOR A VESSEL CLEANING MACHINE

Harry Cunliffe, Leasowe, Wirral, England, assignor to
The Moreton Engineering Company Limited, Moreton,
Wirral, England, a British company

Application February 6, 1957, Serial No. 44,777

Term of patent 14 years

(Cl. D9—6)

Fig. 1 is a perspective view of a scraper for a vessel cleaning machine embodying my new design;

Fig. 2 is a plan view of Fig. 1 in the direction of arrow II;

Fig. 3 is a side elevation in the direction of arrow III of Fig. 1;

Fig. 4 is a side elevation of Fig. 1 in the direction of arrow IV; and

Fig. 5 is a rear end elevation of Fig. 1 in the direction of arrow V.

I claim:

The ornamental design for a scraper for a vessel cleaning machine, substantially as shown.
